FLEXIBLE ATTACHMENT PLUG CAP WITH STRAIN RELIEF

Ross G. Bennett, Fairfield, Conn., assignor to
The Bryant Electric Company, Bridgeport,
Conn., a corporation of Connecticut

Application January 6, 1934, Serial No. 705,589

4 Claims. (Cl. 173—322)

This invention relates to attachment plug caps. More particularly it relates to attachment plug caps made of flexible insulating material such as soft rubber and provided with means for relieving strain put upon the contacts by the usual feed wires.

It is an object of this invention to provide a plug cap of this type with improved means for relieving the strain of the feed wires upon the wire terminals of the prong contacts.

Another object is to provide strain relief means to which the feed wires may be quickly connected after the wires have been connected to the wire terminals of the plug's contact prongs and which will hold the feed wires in an effective manner.

Other objects and advantages of my invention will appear as it is described in connection with the accompanying drawing:

In the drawing:

Figure 1 is a vertical mid-section view through the outside casing of an attachment plug cap constructed according to the principles of my invention.

Figure 2 is a plan view of the contact carrying disc used in my invention.

Figure 3 is an elevation view of the contact carrying disc shown in Figure 2.

Referring to the drawing, the attachment plug cap comprises a tubular outside casing 10 made of insulating material such as soft rubber. This casing is larger at one end than the other and is substantially cylindrical at the large end and tapers into a reduced neck 10a at the small end, through which neck the conductor cord 12 containing feed wires 14 and 16 may pass. The reduced neck 10a of the casing provides convenient means for anyone to grasp the plug for the purpose of connecting it to or disconnecting it from an attachment plug or receptacle. The large end 40 of the casing 10 is provided interiorly with an annular groove 11 which is adapted to receive a flange 13 upon a disc 15 whose diameter is substantially that of the interior diameter of the large end of the casing. The disc 15 may be made 45 of rubber and be sufficiently thick to give substantial rigidity to it. Due to the flexibility of the casing 10 the disc 15 can be inserted into the large end of the casing 10 and removed therefrom by flexing the casing as required. Upon the 50 inner face of the disc 15 there is formed integrally with the disc, a barrier 17 which serves to divide the interior of the casing 10 into two chambers when the disc is in place as shown in Figure 1. The barrier is preferably thinner than the disc 55 and may be subjected to limited flexing or bend-

ing. Symmetrically placed at each side of the barrier 17 are conventional attachment plug contact prongs 18 and 19 which are each provided at one end with a wire terminal as 18a and 19a. Slits are provided in the disc 15 for the accommodation of prongs 18 and 19, the size of the slits being regulated so that when the prongs are inserted therein they will be frictionally held there by the friction between the sides of the slits and the prongs.

Attachment plug caps as just described have heretofore been known. The novel features of my invention will now be described. According to common practice the feed wires 14 and 16 of the conductor cable 12 are secured to the wire terminals 18a and 19a. In order to relieve these wire terminals of strain which is incident to the disconnection of the cap from an attachment plug or receptacle by a person grasping the cable and jerking it, I provide apertures in the barrier 20 10 through which the feed wires 14 and 16 may pass in opposite directions in connecting each with one of the wire terminals 18a and 19a. In order that the feed wires 14 and 16 need not be threaded through the apertures I form the aper- 25 tures with an enlarged inner portion of approximately the same cross sectional area as the cross sectional area of the feed wires and I provide slots 20a and 21a leading from said apertures to the sides of the barrier 17. Since the barrier 30 is made of flexible material and is sufficiently thin to permit flexing, the size of the slots 20a and 21a may be temporarily enlarged by bending up those portions of the barrier which are above the slots so that the feed wires 14 and 16 may 35 be inserted into the apertures 20 and 21 sidewise through the slots. The flexibility of the barrier also makes possible the placing into the apertures of wires whose cross sectional area is larger than the normal area of the apertures.

In order to prevent flexing of the barrier when the disc 15 is inserted in assembled position as shown in Figure 1, the contour of the barrier is made to correspond in a general way with the interior contour of the casing 10, at the part of 45 the casing to which the barrier is adjacent. The engagement of the edge of the barrier with the inside surface of the casing 10 will maintain the edges of the apertures 20 and 21 to grip the feed wires 14 and 16 to insure that the stress of the 50 conductor cord 12 shall be transmitted to the barrier 17.

Thus it will be seen that I have provided a simple and convenient means for engaging feed wires with a strain relief member to relieve the wire 55

5 terminals of the contact prongs of an attachment plug cap of any strain that is put on the feed wires, and this means does not require threading of the wires through apertures in a strain relief member. At the same time I have provided an effective means to cause the strain relief member to grip the feed wires to make more certain of the transmission of any strain of the conductor cord to the strain relief member.

10 By my invention the feed wires may be engaged with the strain relief member either before or after they are fastened to the wire terminals.

15 Modifications and changes in form within the scope of my invention will occur to those skilled in the art therefore I do not limit my invention to the specific form of the invention as illustrated in the drawing.

I claim:—

20 1. An attachment plug cap comprising a casing formed of elastic insulating material, a disc engaged with one end of said casing, prong contacts carried by said disc and having wire terminals on their inner ends, a flexible strain relief member formed integral with said disc and positioned 25 between said wire terminals, said strain relief member being provided with apertures which are connected by slots to the outside edges of said member whereby feed wires may be inserted in said apertures sidewise after the ends of said wires 30 have been connected to said wire terminals, the edges of said apertures exerting a clamping action on said feed wires, and the edges of said barrier engaging with the inside walls of said casing to maintain said clamping action.

35 2. An attachment plug cap comprising a hollow casing member, a disc member in engagement with one end of said casing member, at least one of said members being elastic to permit distortion thereof during the joining together of said members, prong contacts carried by said disc member, a flexible strain relief member secured upon the inner face of said disc member and having apertures for the accommodation of feed wires of a conductor cable, said apertures extending to the

outside edge of said strain relief member to permit a portion of said strain relief member to be turned back for the insertion of feed wires after the feed wires have been connected to said contacts, the edges of said apertures exerting a 5 clamping action on said feed wires, and the edges of said barrier engaging with the inside walls of said casing to maintain said clamping action.

3. An attachment plug cap comprising a hollow casing member, a disc member in engagement 10 with one end of said casing member, at least one of said members being elastic to permit distortion thereof during the joining together of said members, prong contacts carried by said disc member, a flexible strain relief member secured 15 upon the inner face of said disc member and having apertures for the accommodation of the feed wires of a conductor cable and of less width than the diameter of the feed wires, said apertures extending to the outside edge of said strain relief 20 member to permit a portion of said strain relief member to be turned back for the insertion of the feed wires after the feed wires have been connected to said contacts, said strain relief member having its edges in engagement with the inner 25 walls of said casing member when in assembled position.

4. An attachment plug cap comprising a casing of insulating material, a disc positioned in one end thereof, prong contacts carried by said disc 30 and having wire terminals at their ends, a flexible barrier secured on said disc adapted to be engaged by feed wires and to receive strain therefrom, said barrier being positioned between said wire terminals and having apertures extending 35 to the outside edge thereof whereby feed wires may be inserted in said aperture after said wires have been connected to said wire terminals, the edges of said apertures exerting a clamping action on said feed wires, and the edges of said barrier 40 engaging with the inside walls of said casing to maintain said clamping action.

ROSS G. BENNETT.
